UNITED STATES PATENT OFFICE.

HENRY C. BAUSINGER, JR., GEORGE W. FAULKNER, AND JOHN O. TURNER, OF BUCYRUS, OHIO.

PICKER.

Application filed May 15, 1925. Serial No. 30,641.

This invention appertains to attachments for picker sticks and the primary object of the invention is to provide a novel bumper or buffer for the shuttle, which can be 5 readily replaced when worn, with the expenditure of a minimum amount of time and at a small cost.

A further object of the invention is to provide a removable strike plate for the 10 shuttle embodying a novel support for connection with the upper end of the picker stick for detachably receiving the wear or strike plate.

Another object of the invention is the 15 provision of novel means for constructing said support and novel means for detachably connecting the support with the picker stick.

It has heretofore been contemplated in 20 the art of providing a wear or strike member formed of a plurality of layers of heavy sole leather which is difficult and costly to replace. It is therefore a further object of the invention to provide means for associating a relatively small buffer pad with 25 the picker stick of an inexpensive nature which can be readily and quickly replaced in or removed from position.

With these and other objects in view, the 30 invention consists in the novel construction, arrangement and formation of parts, as will be hereinafter more fully described, claimed, and illustrated in the accompanying drawings, in which drawing:

35 Figure 1 is an elevation of the improved device,

Figure 2 is an edge elevation of the same showing the supporting strap therefore broken away,

40 Figure 3 is a detail perspective view of the casing for detachably supporting the buffer pad,

Figure 4 is a detail perspective view of the buffer or strike plate,

45 Figure 5 is a detail section taken on the line 5—5 of Figure 1 looking in the direction of the arrows,

Figure 6 is a detail section taken on the line 6—6 of Figure 1 looking in the direction of the arrows showing the buffer or strike pad in place in its supporting position, and

50 Figure 7 is a fragmentary plan view of the blank from which the support for the casing is made.

Referring to the drawings in detail, wherein similar reference characters designate corresponding parts throughout the several views, the letter A generally indicates the improved device, which comprises 60 a sheet metal support B for engaging the desired edge of the picker stick adjacent to the upper end thereof. The support B, as stated, is made from sheet metal and preferably from a single blank and includes 65 a rear wall 10, a side wall 11 formed integrally on one longitudinal edge thereof, a front wall 12 formed integral with one longitudinal edge of the side wall 11, and a second side wall 13 formed integral with 70 one longitudinal edge of the front wall 12 and an attaching portion 14 which is formed on the free longitudinal edge of the side wall 13. It is to be noted that the front and rear walls 12 and 10 respectively extend a slight distance below the side walls 11 and 13. The blank from which the support is constructed is preferably provided with parallel dividing lines 15 on which the blank is folded and the attaching portion 14 is adapted to be folded about the rear face of the rear wall 10 and can be secured thereto in any desired way. The free longitudinal edge of the rear wall 10 supports an attaching tongue 16, which is 75 folded about the side wall 13 and connected therewith in any preferred way. As clearly shown in Figure 7 the attaching portion 14 terminates below the attaching portion 16 in order to permit these portions to be 80 folded readily about the desired walls of the supporting member.

The extreme upper end of the rear wall is extended a considerable distance above the side and front walls and is enlarged in 95 width to provide the body 17. This body 17 has its longitudinal edges notched as at 18 for the reception of the attaching cuff or sleeve 19 which is adapted to extend about the upper end of the picker stick and is secured thereto in any desired way. When the body portion is folded the same is of a substantial rectangular shape as shown in Figure 5 of the drawings and the upper edge thereof is adapted to receive the casing 20 for the buffer or strike pad 21 which is of substantially same shape as the casing 20. This pad 21 can be formed of any desired material, such as rubber, leather or the like, or if preferred a spring supported 100 105 110

sheet metal plate can be used in lieu thereof. The casing 20 includes a front and a rear wall 22 and 23 respectively and connecting side walls 24 and 25. The side walls 5 are preferably provided with arcuate inwardly directed flanges 26 for supporting the buffer pad 21 and the front wall 23 is provided with an enlarged opening 24 for permitting the striking of the buffer pad 10 by the shuttle. The lower edge of the rear wall 22 is provided with a depending tongue 28 which is adapted to be inserted in the support D. The upper edge of the rear wall 22 is provided with an upwardly and forwardly extending tongue 29. This tongue 15 is provided with an opening 30 for reception of a suitable bolt 31 which is adapted to extend through the cuff or collar 19. Any suitable means such as a nut can be employed for holding the bolt 31 in place.

It is obvious from the foregoing that I have provided a novel means for detachably receiving a buffer or strike plate for shuttles, which will permit the easy removing of 25 the buffer or strike plate with a minimum amount of energy and at an extremely low cost.

Changes in details may be made without departing from the spirit or scope of the 30 invention, but:—

What we claim as new is:

1. An attachment for picker sticks com-

prising a plate, a support carried by the lower end of the plate, the opposite edges of the plate above the support being notched, 35 a cuff arranged to engage the picker stick adapted to fit in the notched portion of the plate, a casing adapted to rest upon the support, means connecting the casing with the cuff, and a buffer pad detachably and removably fitted within said casing.

2. An attachment for picker sticks comprising a plate adapted to engage one face of the picker stick, a support formed on the plate, the opposite edges of the plate above 45 said support being notched, a cuff adapted to be fitted above the picker stick fitted in said notches, a casing arranged to fit upon the support including a rear wall, a front wall having an enlarged opening therein 50 and side walls, the lower ends of the side walls being provided with inwardly directed arcuate supporting flanges, an upwardly and outwardly deflected tongue carried by the upper end of the casing, means detachably connecting the tongue with the cuff, and a pad removably fitted within said casing.

In testimony whereof we affix our signatures.

HENRY C. BAUSINGER, JR.
GEORGE W. FAULKENER.
JOHN O. TURNER.
